UNITED STATES PATENT OFFICE.

CLARENCE W. COLEMAN, OF WESTFIELD, NEW JERSEY; KATHERINE COLEMAN, ADMINISTRATRIX OF SAID CLARENCE W. COLEMAN, DECEASED, ASSIGNOR TO THE HALL SIGNAL COMPANY, A CORPORATION OF MAINE.

RAILWAY SIGNAL-RELAY.

1,066,081.

Specification of Letters Patent.

Patented July 1, 1913.

Application filed September 2, 1908. Serial No. 451,346.

To all whom it may concern:

Be it known that I, CLARENCE W. COLEMAN, a citizen of the United States, residing at Westfield, in the county of Union and

5 State of New Jersey, have invented a certain new and useful Improvement in Railway Signal-Relays, of which the following is a specification, reference being had therein to the accompanying drawings, forming part 10 thereof.

My invention relates to electric relays, particularly for railway traffic-controlling or signaling systems.

The object of my invention is to produce 15 a relay adapted for operation by means of alternating or other periodic electric currents, particularly in connection with electric traffic-controlling systems for controlling the signals or other traffic-controlling 20 devices of railways, in which periodic currents are used in the track circuits or other train controlled circuits, and to produce a relay of this character which shall be reliable in operation and responsive to currents of a comparatively faint character.

One feature of the invention consists in the construction of the armature without the use of iron or other magnetic material whereby it is rendered responsive to periodic current, but not responsive to unidirectional 30 constant current. This result is achieved by the use, in connection with a loop-shaped conductor on the armature, of a field magnet adapted to form a magnetic field in 35 which the lines of force are concentrated in the vicinity of the loop-shaped conductor in such a manner as to have a powerful tendency to impart thereto a motion of translation, owing to the combined inductive and 40 repellent effects of the field on the conductor, and this tendency is utilized to move the armature and actuate the circuit-controlling devices carried thereby.

More specifically, the invention resides in 45 the use, in combination with an armature provided with a loop-shaped conductor, of a field member provided with an energizing winding located at one side of said conductor and with pole pieces formed and ar-

ranged to concentrate the magnetic field in 50 the vicinity of the conductor in a manner to increase the effectiveness of their operation thereon.

The before mentioned features of my invention, together with other features relating 55 to details of construction and operation of the preferred embodiment thereof, will be more particularly described hereinafter.

I will now describe particularly the embodiments of my invention illustrated in the 60 accompanying drawings, and will thereafter point out my invention in claims.

In the drawings Figure 1 is a rear elevation of a relay embodying the present invention. Fig. 2 is a vertical section of the 65 relay on the line $x-x$ in Fig. 1, looking from left to right. Fig. 3 is a diagrammatic representation of a portion of a railway traffic-controlling system in which the relay of Figs. 1 and 2 is used. Figs. 4 and 70 5 are, respectively, a rear elevation and a vertical section, of a portion of an armature of modified form for use in connection with the relay of Figs. 1 and 2. Fig 6 is a dia- 75 grammatic representation of a portion of an electric system in which relays are employed having armatures such as that of Figs. 4 and 5.

My improved relay, as illustrated in the drawings, comprises, generally, a ring-shaped conductor constituting a portion of a pivoted armature, and a field magnet for actuating this conductor. The armature conductor, as shown in Figs. 1 and 2, consists of a continuous flat ring 1 of copper 80 or other highly-conductive material, which is fixed to or integral with an arm 7. The arm is pivoted upon a horizontal axis upon posts 8 projecting from a base plate 9, so that the ring 1 may receive a motion which, 85 throughout its short amplitude, is approximately a motion of translation in a direction perpendicular to the plane of the ring 1. The ring 1 and the arm 7 constitute the armature of the relay.

The field member of the relay comprises a core 2 of iron or other magnetic material which projects at one end into the ring 1, a

shell 5 of which one end 6 substantially surrounds the ring 1, and a yoke portion 4 which connects the core and the pole piece. The core, shell and yoke are represented as 5 of integral structure, except that the end piece 6 of the shell is made separate and removable to facilitate the construction. The core and the shell closely embrace the ring 1, but have sufficient clearance to permit the 10 ring to move in the manner above described. The field is energized by a coil 3 of insulated wire located between the core and the shell and wholly at one side of the armature ring 1. The terminals of this coil are connected 15 with binding posts 10 mounted on the base 9.

As the coil 3 is energized by alternating or other periodic currents provision is made for the prevention of eddy currents in the field magnet by slotting the shell, yoke and 20 core, as illustrated at 39 in Figs. 1 and 2, and the shell is also recessed to admit the arm 7 of the armature. Apart from these insubstantial interruptions the shell and core closely embrace the entire circumference of 25 the armature ring.

The core and the shell are magnetized by current flowing in the field coil, in such a manner that the free end of the core and the adjacent inner circumference of the end 30 6 of the shell constitute magnetic poles. Between these poles a powerful magnetic field is formed, constituting lines of magnetic force which are concentrated in planes connecting the poles and parallel to the 35 plane of the armature ring. A portion of the magnetic lines also connect the poles in curved lines passing outside of the space between the poles.

Since the current in the field coil is periodic in character the magnetic field fluctuates. A part of the magnetic lines pass beyond or outside of, that is, in Fig. 2, to the right of, the armature ring, thus passing 40 axially through the armature ring so as to be interlinked therewith, and as these lines fluctuate in strength they induce electro- 45 motive force in the armature ring resulting in rotative currents therein. Another portion of the magnetic lines pass radially through the body of the ring, and these, acting in conjunction with the induced currents in the ring, cause the ring to be repelled from the field magnet, or to the right 50 in Fig. 2.

55 Contact fingers are mounted on the armature in the ordinary manner in order to utilize the relay to control electric circuits. Two such fingers 11, are shown in Figs. 1 and 2, mounted on posts 12 of insulating 60 material. These fingers are provided with contact springs 13 which engage the front contacts 15 and the back contacts 14 of the relay. The weight of the contact fingers imparts a bias to the armature which causes

the contact springs to engage the back contacts 14 when the field coil is deenergized. When the field coil is energized by a periodic current the springs engage the front contacts 15.

The back contacts are mounted in grooves 70 in a block 16 of insulating material fixed to the base plate 9, and are connected with binding posts 17. The front contacts are carried by overhanging arms 18 mounted in grooves in blocks 19 of insulating material, 75 and are connected with binding posts 20. The contact fingers are connected, by flexible wires 21 with terminal blocks 23 also mounted in grooves in the blocks 19 and connected with binding posts 22.

The relay hereinbefore described may be utilized in various ways in railway-traffic controlling systems. In the arrangement illustrated in Fig. 3, it is used to control railway signals. In this system the rails 26 85 are continuously bonded except that at each signal station one of the rails is interrupted by an insulating joint. At each station is a transformer 27 energized by a suitable alternating current generator 28 and connected, at its secondary terminals, with the two rails respectively, by wires 29 and 30. At each station is a relay, of which the field is indicated generally by the reference number 25, and the terminals of the field coils 90 are connected to the opposite track rails. One contact finger and one front contact 15 of each relay are connected in a local branch of the circuit of the generator 28, in series with the electric motor or controlling mechanism of a signal 32 which has a normal bias to danger position. The track is traversed in a westerly direction by trains, as indicated by the arrow 31. The two stations illustrated, designated as A and B respectively, are typical stations, and in the normal condition of the apparatus current from the transformer 27 at B flows normally through a circuit embracing the two track rails and the field coil of the relay at 100 A, and thus the relay at A is normally energized, the local signal circuit at A is normally closed, and the signal at A is held clear. The signals at B and each succeeding station are also normally held clear by 105 current flowing from the next stations to the west.

If a train enter the block between A and B the wheels and axles act to short-circuit the relay at A, which is accordingly deenergized. The armature thereupon opens the local signal circuit and the signal goes to danger position. The same thing occurs at B when the train passes into the block to the west of B, while the signal at A is again cleared as soon as the relay at A is reenergized.

The relay of the present invention is par-

ticularly adapted for use in connection with traffic-controlling systems for railways not only on account of its sensitiveness to comparatively feeble currents such as are used 5 for the sake of economy, in such systems, but also because, owing to the absence of iron or other magnetic material in the armature, the relay is absolutely inert, except when a periodic current capable of inducing current in the armature is passing 10 through the field coil, and the relay is for this reason absolutely unaffected by any residual magnetism in its field or any direct current which may flow, accidentally or intentionally through the field coil. The relay is, therefore, free from two sources of false operation which must be guarded against in the construction of a safe and reliable traffic-controlling system.

20 While the hereinbefore described arrangement of the relay, in which the relay is sensitive to variations of current in the field magnet, is the preferred embodiment of my invention, particularly where the relay is 25 used in traffic-controlling systems for railways, the arrangement may be modified, without departure from the invention in its broader aspects, by using a constantly energized field and controlling the operation of 30 the relay by controlling the flow of induced currents in the armature. In this arrangement it is necessary to employ an armature in which the circuit followed by the induced currents may be opened and closed. An 35 armature of this character is illustrated in Figs. 4 and 5. Here a coil of insulated wire takes the place of the solid copper ring of Figs. 1 and 2, and this coil is fixed by means of suitable binding material 34, to lugs 35 at 40 the lower end of the arm 7. The terminals 36 of the coil are carried up the arm and may be connected with suitable binding posts.

In a relay of the modified form above described, if the field be constantly energized with a periodic current no effect will be produced on the armature so long as the terminals of the armature coil are disconnected, since no induced currents can flow through 50 the armature coil, but if the armature terminals be connected, through a suitable controlling circuit, the armature will be at once moved as the result of the currents induced in the armature and its controlling circuit.

55 My relay, arranged as last described, may be used in traffic-controlling systems and in other connections, and in Fig. 6 is illustrated a system in which a signaling current is to be repeated from point to point along a line. Three stations are illustrated, designated as A, B and C. The armature circuit of the relay at A is controlled by a key 38, while the field 25 is constantly energized by a transformer 27 fed by a suitable

generator 28. The armature circuit of the 65 relay at B is controlled by the contact finger and a front contact 15 of the relay at A, the armature circuit of the relay at C is controlled similarly by the relay at B, and so on throughout the system. The field mag- 70 nets of the relays at B and C are constantly energized in the same manner as in the case of the relay at A. If now the key 38 be operated to close its circuit the armature of the relay at A will be at once actuated and 75 will close the armature circuit of the relay at B, which will in turn close the armature circuit of the relay at C and so on.

While I have described my improved relay as particularly applicable to and useful 80 in connection with railway-traffic controlling systems it will be apparent that it may be used in various other connections, and in general, various modifications may be made in the embodiment of my invention herein- 85 before described and illustrated in the accompanying drawings within the nature of the invention and the scope of the following claims.

I claim:

1. A relay comprising an armature provided with a conductor adapted to constitute a closed path for periodic currents and having a loop-shaped portion, a field member having an inner pole-piece extending 95 within and arranged in close proximity to the loop-shaped portion of the conductor and a shell having an annular winding-containing space and an outer pole-piece circumferentially surrounding the loop-shaped 100 portion of the conductor, and a winding for magnetizing the pole-pieces arranged within the winding-containing space wholly at one side of the loop-shaped portion of the conductor and of the outer pole-piece, where- 105 by the field member is adapted to generate a field of magnetic lines of force of periodic character including flux lines extending along substantially all radii of the ring-shaped conductor and substantially in the 110 plane thereof and including other flux lines extending substantially in axial direction through said conductor so as to induce circulatory periodic currents therein adapted to re-act on said radial flux lines.

2. A relay comprising an armature provided with a conductor adapted to constitute a closed path for periodic currents and having a loop-shaped portion, a field member having an inner pole-piece extending 120 within and arranged in close proximity to the loop-shaped portion of the conductor and a shell having an annular winding-containing space and an outer pole-piece circumferentially surrounding the loop-shaped 125 portion of the conductor and extending across the winding-containing space of the field member from the shell to within close

proximity of the loop-shaped portion of the conductor, and a winding for magnetizing the pole-pieces arranged within the winding-containing space wholly at one side of the loop-shaped portion of the conductor and of the outer pole-piece.

In testimony whereof I have affixed my signature in presence of two witnesses.

CLARENCE W. COLEMAN.
